Primary Examiner — Ryan Harvey(74) *Attorney, Agent, or Firm* — Southeast IP Group;
Thomas L. Moses(57) **CLAIM**

The ornamental design for the weight sled, as shown and described.

DESCRIPTION

FIG. 1 is a top view of my design for a weight sled;
FIG. 2 is a bottom view thereof;
FIG. 3 is a top view thereof;
FIG. 4 is a bottom view thereof;
FIG. 5 is a perspective top view thereof;
FIG. 6 is a perspective bottom view thereof;
FIG. 7 is a right view thereof; and,
FIG. 8 is a left view thereof.

The claimed design is shown with a symbolic break in its length. The appearance of any portion of the article between the break lines forms no part of the claimed design. The broken lines depict stitching and form no part of the claim.

1 Claim, 7 Drawing Sheets
